UNITED STATES PATENT OFFICE

2,321,097

AIR OR GAS COMPRESSOR

Edward Cecil Mills, Camborne, England

Application December 30, 1941, Serial No. 424,910
In Great Britain December 23, 1940

8 Claims. (Cl. 123—119)

This invention relates to air or gas compressors driven by internal combustion engines.

One object of the invention is the provision, in a simple way, for efficient cooling of the layout.

Another object is the provision of a simple way of means for supercharging the engine and/or the compressor.

Other objects and advantages will appear hereinafter.

According to the invention the cylinders of the engine and compressor are cooled by a current of cooling fluid produced by a fan or other pump driven by the engine, the current of fluid being led through ducting by which the correct proportions are supplied to the respective cylinders.

The invention further resides in the arrangement that air for supercharging the engine or the compressor is supplied by a fan (which may be the same fan as the above) driven by the engine.

In order that the invention may be more clearly understood a portable layout of a compressor driven by an internal combustion engine in accordance with the invention will now be described, reference being made to the accompanying drawings, wherein—

Figure 1 is a side elevation of said layout.

Figure 2 is an end view of the same looking from the right of Figure 1.

Figure 3 is a plan of the same.

Figure 4 is a section on the line IV—IV of Figure 3.

Figure 5 is a section on the line V—V of Figure 1.

Figure 6 is a section on the line VI—VI of Figure 3.

Figure 7 is a side elevation sectioned in such a way as to show the flow of air to supercharge the engine and compressor cylinders.

Figure 8 is a side elevation sectioned in such a way as to show the passage of air from the low pressure to the high pressure stage of the compressor through the intercooler.

Referring to these drawings, the portable layout is the same as that described and illustrated in my co-pending application Serial No. 424,909, filed December 30, 1941 (corresponding to British patent application No. 18,034/40) and comprises an air or gas compressor having a vertical cylinder 1 and an internal combustion engine having vertical cylinders 2 and 3 for driving said compressor. The compressor and motor have a common crank shaft indicated at 4a, or the two crank shafts are coaxial and directly coupled together.

The compressor is of the single cylinder two stage, double acting type, and an intercooler 4 is

provided, the air after the first stage of compression flowing as best shown in Figure 8, from the upper end of the cylinder 1 by way of a conduit 5 to the upper end of the intercooler 4 and from the lower end of said intercooler by way of a conduit 6 to the lower end of said cylinder 1 for the second stage of compression. Said intercooler is arranged as shown alongside the cylinders 2 and 3 of the engine. An aftercooler 7 is also provided, the air, after the second stage of compression, passing as best shown in Figure 4, from the lower end of the cylinder 1, by way of a conduit 8, to the lower end of the half of the aftercooler tubes nearest the cylinder, and from the upper end of the said half of the aftercooler tubes by way of a conduit 9 to the upper end of the other half of the aftercooler tubes, and from the lower end of the said other half of the aftercooler tubes, by way of a conduit 9a to the point of use. Said aftercooler is arranged as shown in Figure 3 at the side of the cylinders remote from the intercooler, and at a position about between the cylinders 1 and 3.

The compressor, internal combustion engine, intercooler and aftercooler may be of conventional design and no further description of them is deemed necessary. The present invention is primarily concerned with the cooling of the engine, compressor, intercooler and aftercooler, and also with the supercharging both of the engine and of the compressor with air at a little above atmospheric pressure.

For this purpose a centrifugal fan 10 is mounted on the shaft 4a (secured for example to the engine fly wheel 30) at the end remote from the compressor. Cooling air is sucked in an axial direction into the fan casing 11 as indicated by the plain arrows in Figures 1, 3 and 7. From the left-hand side of the fan casing 11 (as seen in Figure 2) duct for cooling air extends first upwards at 12, then turns longitudinally horizontally at 13 (Figures 1, 3, 7 and 8), then turns horizontally inwardly at 14 (Figures 2, 3, 4 and 6), embracing within itself the intercooler 4 as shown and continues inwardly embracing within itself the cylinders 2 and 3. These cylinders are provided with vanes 15. Thus the cooling air flowing along this duct cools the intercooler 4 and the cylinders 2 and 3.

This duct is built up of plating and is generally of rectangular cross-section as shown. The roof of said duct is seen to terminate at 16 (Figures 3 and 6) short of the axes of the cylinders 2 and 3. The floor of the duct is constituted by the top of the crank case. The right-hand wall

of said duct (as seen in Figure 3) terminates at the point 17 beyond the axes of said cylinders. The other wall 18 (Figures 3 and 4) proceeds beyond said cylinders for a purpose which will hereinafter appear.

This wall 18, which passes between the cylinders 1 and 3 is louvred as indicated at 18a, at the region beyond the intercooler 4 to enable the correct proportion of cooling air to flow through, as indicated by the plain arrows in Figure 3, for the purpose of cooling the cylinder 1 and after-cooler 7. This cooling air leaving the louvres is guided by further ducts to flow round the cylinder 1 and its vanes 19, as shown in Figures 3 and 4, said further ducts consisting of side plates 20 and a top plate terminating at 21 (Figure 3), the bottom of the duct being constituted by the top of the crank case. A branch of the same cooling air in the correct proportion is guided to flow over the aftercooler 7 by means of further ducts consisting of side plates constituted respectively by the extension of the aforesaid plate 18 and by a plate 22 (Figures 3 and 4) and corresponding top and bottom plates.

It will be noted that the conduits 5 and 6 extending between the cylinder 3 and the intercooler 4 run close to the ducts guiding the cooling air to the intercooler, which arrangement further increases the cooling effect.

The system is also provided with an oil cooler 23 in the form of a vaned sump, and additional ducting 24 (Figures 1 and 5) extends from the fan casing 11 to and around this vaned sump, guiding the air over the vanes thereof.

Some of the air from the cooling fan 10 is also used to supercharge both the engine and the compressor. To this end a conduit 25 branches, at the region 13, as best seen in Figure 7 from the top of the duct leading from the fan casing to the intercooler 4, and leads to the inlet 26 of the compressor cylinder 1; and, from this conduit 25, branches a conduit 27, which forks and leads to the inlets 28 and 29 of the cylinders 3 and 2 as indicated.

Although the air pressure at the fan discharge will be but a few inches of water, it will supercharge slightly both the engine and the compressor and also ensure a supply of the coolest available air.

Structural details are deemed sufficiently clear from the drawings.

It will be appreciated that the cooling system described provides efficient cooling with simplicity of design, permitting complete elimination of the usual radiation and water cooling system.

What I claim and desire to secure by Letters Patent is:

1. A gas or air compressor driven by an internal combustion engine, comprising, in combination with a crank shaft, a compressor cylinder and a plurality of combustion engine cylinders, pistons in said cylinders connected to said crank shaft, an air duct embracing said combustion engine cylinders for cooling same, a fan carried by said crank shaft for circulating cooling air above atmospheric pressure through said duct, louvres in said duct adjacent said compressor cylinder for directing air upon said compressor cylinder to cool same, and branch conduits leading from said air duct to the inlets of said combustion engine cylinders and said compressor cylinder for supercharging same.

2. A gas or air compressor driven by an internal combustion engine, comprising, in combination with a crank shaft, a compressor cylinder

and a plurality of combustion engine cylinders, pistons in said cylinders connected to said crank shaft, an air duct embracing said combustion engine cylinders for cooling same, a fan carried by

5 said crank shaft for circulating cooling air above atmospheric pressure through said duct, louvres in said duct adjacent said compressor cylinder for directing air upon said compressor cylinder to cool same, and branch conduits leading from a 10 region of said air duct in advance of said combustion engine cylinders and connected to the inlets of said combustion engine cylinders and said compressor cylinder for supercharging same with cool air.

15 3. A gas or air compressor driven by an internal combustion engine, comprising, in combination with a crank shaft, a two stage compressor cylinder and a plurality of combustion engine cylinders, pistons in said cylinders connected to

20 said crank shaft, an intercooler connected between the two stages of said compressor cylinder means including an air duct embracing said combustion engine cylinders and said intercooler for cooling same, and branch conduits leading from said air duct to the inlets of said combustion engine cylinders and said compressor cylinder for supercharging same.

25 4. A gas or air compressor driven by an internal combustion engine, comprising, in combination with a crank shaft, a two stage compressor cylinder and a plurality of combustion engine cylinders, pistons in said cylinders connected to said crank shaft, an intercooler connected between the two stages of said compressor cylinder, an aftercooler connected to the second stage of said compressor cylinder, means including an air duct embracing said combustion engine cylinders and said intercooler for cooling same, and means associated with said duct for directing a portion of the air therein upon said compressor cylinder and said aftercooler for cooling same.

30 5. A gas or air compressor driven by an internal combustion engine, comprising, in combination with a crank shaft, a two stage compressor cylinder and a plurality of combustion engine cylinders, pistons in said cylinders connected to said crank shaft, an intercooler connected between the two stages of said compressor cylinder, an aftercooler connected to the second stage of said compressor cylinder, means including an air duct embracing said combustion engine cylinders and said intercooler for cooling same, means associated with said duct for directing a portion of the air therein upon said compressor cylinder and said aftercooler for cooling same, and branch conduits leading from said air duct to the inlets of said combustion engine cylinders and said compressor cylinder for supercharging same.

35 6. A gas or air compressor driven by an internal combustion engine, comprising, in combination with a crank shaft, a two stage compressor cylinder and a plurality of combustion engine cylinders, pistons in said cylinders connected to said crank shaft, an intercooler connected between the two stages of said compressor cylinder, an aftercooler connected to the second stage of said compressor cylinder, an air duct embracing said combustion engine cylinders and said intercooler for cooling same, a fan carried by said crank shaft for circulating cooling air above atmospheric pressure through said duct, louvres in said duct adjacent said compressor cylinder and said aftercooler for directing air thereover to cool same, and branch conduits leading from a region of said air duct in advance of said combustion engine cylinders and

connected to the inlets of said combustion engine cylinders and said compressor cylinder for supercharging same with cool air.

7. A gas or air compressor driven by an internal combustion engine, comprising, in combination with a crank shaft, a compressor cylinder and a plurality of combustion engine cylinders, pistons in said cylinders connected to said crank shaft, an oil sump beneath said crank shaft, means including an air duct embracing said combustion engine cylinders for cooling same, means associated with said duct for directing a portion of the air therein upon said compressor cylinder for cooling same, branch conduits leading from said air duct to the inlets of said combus-

tion engine cylinders and said compressor cylinder for supercharging same, and a branch conduit leading from said air duct to said oil sump for cooling same.

5 8. A gas or air compressor driven by an internal combustion engine, comprising, in combination with a crank shaft, a two stage compressor cylinder and a plurality of combustion engine cylinders, pistons in said cylinders connected to said crank shaft, an intercooler connected between the two stages of said compressor cylinder, and means including an air duct embracing said combustion engine cylinders and said intercooler for cooling same.
